UNITED STATES PATENT OFFICE.

WILLIAM T. LAWLOE, OF JERSEY CITY, NEW JERSEY.

RAILWAY-SWITCH HEATER.

1,401,798.

Specification of Letters Patent Patented Dec. 27, 1921.

Application filed March 31, 1921. Serial No. 457,231.

To all whom it may concern:

Be it known that I, WILLIAM T. LAWLOE, a citizen of the United States, and a resident of Jersey City, in the county of Hudson and 5 State of New Jersey, have invented a new and Improved Railway-Switch Heater, of which the following is a full, clear, and exact description.

This invention relates to improvements in 10 railway switch heaters, and has particular reference to devices of the character illustrated in Letters Patent of the United States, #1,327,483, issued to me on January 6th, 1920, said patent disclosing a device in 15 which a plurality of open topped oil pans are located between the ties of a railroad under the rails of a switch mechanism, and in which oil is burned in the pans to keep the switches open and in working order during 20 heavy snowstorms.

In these devices, the oil feed pipe enters the pan below its upper edge. It has been discovered that during warm weather rain collects in the pans and when a sudden 25 change in temperature occurs, the rain water in the pans freezes and blocks the fuel inlets so that it is necessary to pick the ice out of the pans in order to permit a flow of fuel.

It is an object of this invention, therefore, 30 to provide covers for the pans, which will prevent water from collecting therein during rainstorms, and which may be quickly moved out of the way when the pans are in use.

35 A still further object is to provide means for simultaneously operating all of the pan covers and to provide covers and operating mechanisms therefor, which will be simple and practical in construction, strong and durable in use, and comparatively inexpensive to manufacture.

With these and other objects in view, the invention consists in certain novel features of construction and combinations and arrangements of parts as will be more fully 45 hereinafter described and pointed out in the claims.

In the accompanying drawings:—

Figure 1 is a plan view of a fragment of 50 a railway switch and adjacent parts showing my improved heater in applied position;

Fig. 2 is a vertical transverse section on the line 2—2 of Fig. 1;

Fig. 3 is a top plan view of one of the

pans illustrating the details of the pan cover 55 and its actuating mechanism;

Referring more specifically to the drawings I show a conventional arrangement of cross ties 10 spaced from one another and upon which the stock rail 11, switch rail 12, 60 and movable switch points 13 and 14 are supported in any well known or approved manner.

15 indicates a reservoir adapted to contain any suitable supply of liquid fuel such as 65 crude oil or the like, the same being adapted to be conveyed to and along the switch mechanism by means of a transverse pipe 16 and parallel longitudinal pipes 17 and 18, shown as supported upon the end portions of the 70 cross ties on opposite sides of the railway rails. These longitudinal pipes may be secured in a fixed position with respect to the rails by means of clips 19 fixed to certain of the ties.

The improved pan or receptacle for the liquid fuel is shown as a whole at 20 and comprises a semi-cylindrical body 21 having a rounded bottom and vertical end walls 22, shown as rectangular in form and having 80 their lower edges 22' lying in the same horizontal plane and serving as means to support the pan firmly upon the ballast 23 below and between the ties. Thus it will be seen that the end walls 22 not only serve to 85 close the receptacle body at the ends but constitute downward extensions below the rounded convex bottom of the pan. One side of the pan body is provided with a nipple 24 having a port 25 opening into the hollow interior of the pan along which the liquid fuel may be caused to drip or pour from a tube 26 leading from one of the side pipes 17, the quantity of the oil delivered 90 being regulatable delicately by the adjustment of a valve 27 seated in each of the tubes 26.

The invention in this case resides primarily in the provision of flat covers 28 for the pans. Channel guide blocks 29 are secured upon the end walls of the pans and the covers 28 are slidable between the guide blocks. The pan covers include at each end a forwardly presented arm 30. When the covers are pulled back to permit the burning 105 of fuel in the pans, the arms 30 will serve to prevent the covers from complete disengagement with the pans and will guide the move-

ment of the covers incidental to again closing the pans.

I do not wish to be limited to any particular means for operating the covers, but I have illustrated one practical mechanism for simultaneously operating all of the covers of one series of pans.

Located upon the ends of the cross ties 10, are split bearing blocks 31, in which 10 crank shafts 32 located in parallelism with the pipes 17 and 18 are mounted. Relatively short crank arms 33 are rigidly connected to the crank shafts 32. A crank lever 34 is provided at the end of each 15 shaft 32 for operating the arms. Brackets 35 are secured upon the rear ends of each cover and links 36 are pivotally connected at one end to the crank arms 33 and at their other ends to the brackets.

20. It will thus be seen by swinging the crank levers 34, the pan covers 28 will be simultaneously operated through the medium of the crank arms 33 and the links 36.

Various slight changes and alterations 25 might be made in the general form and arrangement of the parts described without departing from the invention, and hence I do not wish to limit myself to the precise details set forth, but shall consider myself 30 at liberty to make such slight changes and alterations as fairly fall within the spirit and scope of the appended claims.

I claim:

1. In a heating device for railway 35 switches, the combination with a system of pipes, a reservoir from which said pipes are adapted to convey fluid fuel, and a plurality of open topped pans located beneath the rails and communicating with the pipes, of 40 covers adapted to cover the tops of the pans, and means for simultaneously operating the covers.

2. In a heating device for railway 45 switches, the combination with a system of pipes, a reservoir from which said pipes are

adapted to convey fluid fuel, and a plurality of open topped pans located beneath the rails and communicating with the pipes, of channel guide members carried by the pans, pan covers slidable in the guide members, and means for simultaneously operating all of said covers.

3. In a heating device for railway switches, the combination with a system of pipes, a reservoir from which said pipes are 55 adapted to convey fluid fuel, and a plurality of open topped pans located beneath the rails and communicating with the pipes, of channel guide members carried by the pans, pan covers slidable in the guide members, and means for simultaneously operating 60 all of said covers, said means comprising a crank shaft, crank arms carried by the crank shaft, means operatively connecting the crank arms and covers, and means for 65 operating the shaft.

4. In a heating device for railway switches, the combination with a system of pipes, a reservoir from which said pipes are adapted to convey fluid fuel, and a plurality 70 of open topped pans located beneath the rails and communicating with the pipes, of channel guide members carried by the pans, pan covers slidable in the guide members, and means for simultaneously operating all 75 of said covers, said means comprising a crank shaft, a crank lever fixed to the shaft, crank arms carried by the shaft, brackets fixed to the pan covers, links pivotally connected to the brackets and crank arms.

5. The herein described track heating receptacle, comprising an open topped body having closed sides and ends, channel guide members supported upon the ends of the body, a cover slidable between the channel 85 guide members and a pair of forwardly presented arms forming continuations of the ends of the cover and normally extending beyond the forward edge of the receptacle.

WILLIAM T. LAWLOR.
